UNITED STATES PATENT OFFICE.

OTTO ROLAND, OF HANOVER-LINDEN, GERMANY.

LOCK.

997,705.

Specification of Letters Patent. Patented July 11, 1911.

Application filed March 8, 1911. Serial No. 613,016.

To all whom it may concern:

Be it known that I, OTTO ROLAND, a subject of the German Emperor, residing at Hanover-Linden, in Germany, have invented 5 a certain new and useful Improvement in Locks, of which the following is a specification.

This invention relates to locks of the type wherein a key-operated bolt, that is to say 10 a bolt adapted to be retracted by means of a key, is automatically shot into locking position by a spring, when released from a restraining device by the movement imparted to a latch bolt by the act of closing 15 the door.

The invention provides a lock wherein the said restraining device is unaffected by the inward movement of the latch-bolt, but is disengaged by the forward or outward movement of said latch-bolt. This insures that 20 the key-operated bolt is not released until it is properly in line with the recess provided for it in the keeper.

The invention is illustrated in the annexed drawings, in which—

Figure 1 is an elevation showing the interior of the lock, and Fig. 2 an elevation viewed at right angles to the plane of Fig. 1, showing the bolts in front view.

30 In the drawing *a* is the latch bolt retracting spindle, apertured for engagement with a handle or door-knob; *b* is the latch-bolt, to which the pendent dog *c* is pivoted within the recess *c*¹. The latter is somewhat wider 35 than the dog and is cut aslant, so that the dog can swing from the perpendicular toward the right of Fig. 1, but cannot swing toward the left. The double armed lever *d* acted on by the spring *d*¹ engages the notch 40 *d*² in the retracted key-operated bolt *e*, and thus prevents the shooting of the latter into locking position by the spring *f*. The recess *h* in the bolt *e* enables the latter to be locked 45 in the retracted position by the vertical bolt *g* of the small auxiliary lock *i*. The keeper

k has spring-pressed plates serving as abutments for the bolts *b* and *e* when they are shot into locking position.

The action of the device is as follows. When on the closing of the door the latch 50 bolt is thrust inward, *i. e.* toward the left of Fig. 1, the dog *c* yields and trips over the lever *d* without moving same. But when the latch bolt shoots forward into the recess in the keeper, the dog, unable to yield, actuates the lever *d* and disengages same from the bolt *e*, whereupon the latter is shot into locking position by the spring *f*.

What I claim as my invention and desire to secure by Letters Patent of the United 60 States is:—

1. In a lock the combination of a latch bolt, a bolt adapted for retraction by a key, a spring operating to thrust said key-operated bolt into locking position, a restraining device which automatically engages the retracted key-operated bolt, and a device actuatable by the outward movement of the latch bolt for disabling said restraining device.

2. In a lock the combination of a latch bolt, a bolt adapted for retraction by a key, a spring operating to thrust said key-operated bolt into locking position, a spring-pressed restraining lever which automatically engages the retracted key-operated bolt, and a dog pivoted to the latch bolt so as to have limited movement about its pivot, so that said dog can trip over the restraining lever during inward movement of the latch 75 bolt, but disengages said lever from the key operated bolt during outward movement of the latch bolt.

In witness whereof I have signed this specification in the presence of two witnesses. 80

OTTO ROLAND.
